EDWIN SHEPPARD, OF PHILADELPHIA, PENNSYLVANIA.

Letters Patent No. 82,357, dated September 22, 1868.

AUTOMATIC BOILER-FEEDER.

The Schedule referred to in these Letters Patent and making part of the same.

TO ALL WHOM IT MAY CONCERN:

Be it known that I, EDWIN SHEPPARD, of Philadelphia, Pennsylvania, have invented an improved Automatic Boiler-Feeder; and I do hereby declare the following to be a full, clear, and exact description of the same.

My invention consists of a certain arrangement of cylinders or casings applied to a steam-boiler, and communicating with each other, and with the interior of the said boiler, as fully described hereafter, the said cylinders being provided with suitable pistons, floats, and piston-rods, so connected with the valve-lever of a water-pipe as to regulate the supply of water to the boiler, and maintain an even and proper water-level within the same.

In order to enable others familiar with apparatus of this class to make and use my invention, I will now proceed to describe its construction and operation, reference being had to the accompanying drawing, which forms a part of this specification, and in which—

Figure 1 is a vertical section of my improved automatic boiler-feeder.

Figure 2, the same, with the parts in a different position.

Figure 3, a vertical section on the line 1-2, fig. 1, showing the parts of the apparatus in a third position.

Figure 4, a detached view drawn to an enlarged scale; and

Figures 5, 6, and 7, views representing modifications of my invention.

Similar letters refer to similar parts throughout the several views.

A represents a portion of the head of a steam-boiler, to the front of which is secured, in any suitable manner, a cylinder or casing, B, which communicates with the interior of the boiler at two points, above and below the average water-line x , by means of pipes a a' , fig. 3. The water within the boiler has at all times free access to the interior of the cylinder through the pipe a , and the steam through the pipe a' , so that the same water-level is necessarily maintained in both boiler and cylinder, and in the front of the latter are the usual gauge-cocks b b b , by which the height of the water may at any time be determined.

The lower end of the cylinder B is closed, and to its upper flanged end is bolted a head, c, having a stuffing-box, c' , through which is arranged to slide vertically a tubular rod, C, the latter being secured near its lower end to a float, D, within the cylinder by means of arms e .

The float D consists of a vessel of thin metal, open at the top, and arranged to rise and fall with the water in the cylinder, being guided and maintained in a proper vertical position by the tube C, and by a rod, f, which passes through an opening in a cross-bar, f' , and the lower open end of the tubular rod C extends into a well or reservoir, g, formed in the bottom of the float, for a purpose described hereafter.

Directly over the cylinder B, and secured to the same by supports or legs h , is a smaller cylinder, F, open at each end, as shown in fig. 4, and arranged for the reception of two pistons, i and i' , one above the other, and secured to the tubular rod C, the latter being closed at the top, and having, between its pistons i and i' , openings j , from which, under the circumstances described hereafter, steam may pass through the cylinder F into a pipe, k, and thence to a third cylinder, G, which may be secured directly to the head of the boiler, or to one of the other cylinders, and is provided at its lower end with a detachable head and stuffing-box l .

Within this cylinder is a piston, m' , the rod, m , of which passes through the stuffing-box l , and through an opening, n , in the upper end of the cylinder, the said opening being of somewhat greater diameter than the rod, for a purpose described hereafter.

The piston-rod m is connected by a rod, p , to a weighted lever, H, which is connected to a valve of suitable construction in the feed-water pipe J.

Whatever may be the water-level, and the position of the float in the cylinder B, the steam contained in the upper portion of the latter will pass to the bottom of the float, enter the lower open end of the tubular rod C, and will rise through the rod, and pass out at its openings j into the cylinder F, between the pistons i and i' .

When the water, therefore, is at the proper level in the boiler, (indicated by the red line x x .) the float, its tubular rod C, and the pistons i and i' , will assume the position shown in fig. 1. The steam, entering the cyl-

inder F between its pistons, will pass through the pipe k, and elevate the piston m' to the upper end of the cylinder G, and the air confined in the latter, above the piston, will be forced in small quantities through the opening n, and will serve as a cushion to prevent the piston from being too suddenly elevated by the action of the steam beneath it.

When the piston m' is thus elevated in its cylinder, the weighted lever H is, through the medium of the rod p, raised to the position shown in fig. 1, when the valve within the feed-water pipe J is so operated as to allow a proper supply of water to pass through the said pipe to the boiler.

If the water within the boiler should rise to a point above its proper level x x, for instance, to the height represented by the line y, fig. 2, there will be a corresponding elevation of the float and its tubular rod, the pistons i and i' being moved to a position above the pipe k, so that the steam within the cylinder G can return through the pipe into the cylinder F, and escape from the lower end of the same.

As soon as the pressure of steam is removed from beneath the piston m', the latter will, together with the weighted lever H, fall to the position shown in fig. 2, when the valve within the pipe J will be closed, and the supply of water cut off from the boiler.

The valve will remain thus closed until the water within the boiler falls sufficiently to permit the piston i' to assume its first position beneath the pipe k, steam then passing into the cylinder G, elevating its piston m', and operating the valve-lever H, as before described, so as to again turn on the supply of water to the boiler.

If, by any accident, the water should fall in the boiler to a point considerably below the line x x, the float D will also descend until it rests upon the cross-bar f', which, as shown in fig. 3, prevents the piston from descending below the pipe k, and serves to hold the piston i' at a point so close to the bottom of the cylinder F that the steam, escaping between the latter and the said piston, will cause sufficient of an alarm to call the attendant to his duty, if he be within hearing-distance.

The recess g, at the bottom of the float, into which the lower end of the tubular rod C enters, serves as a reservoir for any steam that may become condensed within the said float, the water in the reservoir being forced upwards through the rod C by the pressure of steam, and discharged from the openings j.

In the modification of my invention, shown in fig. 5, the piston or float-rod C is solid, steam being admitted into the cylinder F through a pipe, s, from the cylinder B; and another modification, by which the apparatus may be simplified and made more compact, is shown in figs. 6 and 7.

In the latter case the cylinders F and G are cast together in one piece, as shown best in fig. 7, and are secured at some convenient point above the boiler, the cylinder B being dispensed with, while the rod C passes through the top of the boiler, and its float, D, rests directly upon the surface of the water within the same.

In this case also steam may be admitted into the cylinder G at one of the two points t and t', either above or below its piston, according to the positions of the pistons i and i', the port t' serving as an exhaust-port when steam is admitted through the port t, and *vice versa*. By this means the piston m' is both raised and lowered by the action of the steam, and the weight at the outer end of the valve-lever H may be dispensed with.

The above apparatus is entirely automatic in its action, and will maintain the water within the boiler at a uniform or nearly uniform level.

Without confining myself to the precise arrangement and construction of parts herein described, I claim as my invention, and desire to secure by Letters Patent—

An automatic boiler-feeder, consisting of a cylinder, B, with its float D, cylinder F with its pistons i i', operated by the float D, and cylinder G with its piston m', the cylinder F communicating with the cylinder G, and the cylinder B with the cylinder F, and the whole being arranged and applied to a steam-boiler, to regulate the flow of water to the same, substantially as described.

In testimony whereof, I have signed my name to this specification in the presence of two subscribing witnesses.

EDWIN SHEPPARD.
